(57) **CLAIM**

The design related to guns, compressed air guns or gun models, for example gun toys, and gun portions, as shown and described.

DESCRIPTION

FIG. 1 is a portional front perspective view of a design related to guns, compressed air guns or gun models, for example gun toys, and gun portions showing a new design for this portion alone;

FIG. 2 is a portional rear perspective view of the design related to guns, compressed air guns or gun models, for example gun toys, and gun portions showing a new design for this portion alone;

FIG. 3 is a portional left side view of the design related to guns, compressed air guns or gun models, for example gun toys, and gun portions showing a new design for this portion alone;

FIG. 4 is a portional right side view of the design related to guns, compressed air guns or gun models, for example gun toys, and gun portions showing a new design for this portion alone; and,

FIG. 5 is a portional top view of the design related to guns, compressed air guns or gun models, for example gun toys, and gun portions showing a new design for this portion alone.

The broken lines shown are included for the purpose of illustrating the unclaimed portions of the article and form no part of the claimed design.

1 Claim, 5 Drawing Sheets
